(57) **CLAIM**

The ornamental design for a billiard table, as shown and described.

DESCRIPTION

FIG. 1 is a perspective view of a billiard table, showing my new design;

FIG. 2 is a right-hand side elevational view, wherein the left-hand side elevational view is substantially identical;
FIG. 3 is an end elevational view, wherein the opposite end elevational view is substantially identical;

FIG. 4 is a top plan view; and,

FIG. 5 is a bottom plan view thereof.
